WIRE TIGHTENER

John A. Snodgrass, Prescott, Ark., assignor of
one-fourth to A. C. Stuart and two-fourths to
E. W. Stuart, both of Texarkana, Tex.

Application February 6, 1939, Serial No. 254,768

4 Claims. (Cl. 254—82)

My invention relates to tools for constructing new wire fences and for tightening and repairing old wire fences.

An object of this invention is to provide a tool by means of which the slack in a line of fence wire may be taken up and held taut until the operator has been able to secure the tightened fence wire to the post with a tying wire.

Another object of this invention is to provide a tool for stretching wire.

My invention will be more readily understood from a reading of the following specification, referring to the accompanying drawings in which examples of my invention are illustrated wherein:

Figure 1 is a plan view of the preferred form of the invention;

Figure 2 is a side elevation view of the preferred form of the invention;

Figure 3 is a side view showing the step of operating the invention;

Figure 4 is a bird's-eye view showing my invention in position for operating;

Figure 5 is an elevation view of a wire fence that has been tightened with the use of my invention;

Figure 6 illustrates a simple wire stretcher in operation, also embodying my invention;

Figure 7 illustrates the simple wire stretcher of Figure 9, in use combined with the preferred form 30 of my wire tightener, and;

Figure 8 shows an example of fence repair wherein old wire has been stretched with my invention and then spliced.

In the drawings herein, Figures 1, 2, 3, 4, 5, 35 6, 7 and 8 illustrate the preferred form of my invention; numeral 1 designates an elongated lever bar, preferably made of hollow steel tubing. Lever bar 1 has its forward flattened end expanded to form a spur 2, adapted to serve as a fulcrum 40 point and is sharp enough to dent a wooden post or the like to maintain its position. The lever bar 1 is provided with a series of slotted holes 3 which are adapted to receive the hook prong 5 of the yoke 4 for various adjusted positions of the yoke 4 with respect to the lever 1. Linked to the yoke 4 there are two long grab hooks 6 which are adapted to hook over a strand of fence wire F or the like, as illustrated by Figures 3 and 4 of the drawings. The invention thus far described 45 constitutes a useful tool for stretching wire around the two sides of a post as illustrated by Figures 3, 4 and 5 and could be used for stretching wire lengthwise as illustrated by Figures 7 and 8. Applicant's invention, however, amounts 50 to more than this, in that he has provided in his

construction a bracing dog 7 which serves to keep the lever from being pulled back by the tension of the stretched wire. It is readily seen that by means of the bracing dog 7 the operator may release his hand from the lever and be free to use both hands to make secure the tension in the fence wire F with the tie wire T, as seen in Figure 5 of the drawings, or to make a splice in fence wire F, as seen in Figure 8 of the drawings. The bracing dog 7 is provided with a curved spur 8 similar to spur 2 of the lever 1 and for a similar purpose. I have pivoted my bracing dog 7 near the spur end of the lever 1 by means of a pivot 9. Preferably the pivot 9 is put through the handle 1 on a diameter at a right angle to the plane of the slot 10 in the lever 1 for the bracing dog 7 to work in and out of. I get the best results by cutting the slot 10 to a depth of approximately half the diameter of the lever at the spur end. This feature is quite important and is quite an advancement in this art, in that by means of this construction I am able to use my invention very close to the top of a fence post. This comes about by the fact that the spur 2 of the lever 1 can be placed close to the top of a post since the dog 7 can be closed down through the slot 10 to permit its spur 8 to rest at a point immediately above spur 2 of the lever 1.

In the operation of this preferred form of my invention the first step is to place the lever 1 into position with its spur 2 in engagement with a post P, or the like, disposed at an upward inclination. The next step is to engage the hooks 6 over fence wire F, then pull by hand all of the slack you can out of the wire and fasten the prong 5 of the yoke 4 into the nearest slotted hole 3 it reaches to. In this position of the lever 1, the bracing dog 7 should be opened as far out of the slot 10 as it can be. When the lever 1 is swung downwardly the wire is drawn around each side of the post as indicated by Figure 3 and Figure 5, or it may be stretched lengthwise as shown by Figures 1 and 8. The bracing dog 7 is designed to work loosely about its pivot 9 and through its receiving slot 10 so that it will follow the lever down by the force of gravity only, to the proper position for checking the tension of the wire and supporting the lever 1 in the position it is drawn down to. The last step in the operation, as briefly mentioned above, is the step of securing the tension in the stretched fence wire F, by means of the tie wire T which wire is tightly wrapped around the fence wire F at positions to and from post P and about the oppo- 55

site side of the fence post P that the fence wire F runs.

Figures 6, 7 and 8 illustrate another form of my invention. In setting forth with this form of the invention, I am not laying claims of being the originator of a wire gripping device in and of itself but I do claim to be the originator of a wire gripping device with a loop chain extending from the wire gripping device. In Figure 8, numeral 50 designates a wire gripping device; numeral 51 designates a loop chain extending from the same. This device is useful in and of itself as a wire stretching device by the simple use of a lever which may be interposed between the chains and a post for stretching wire. It can be used very conveniently with the preferred form of my invention heretofore described. In its use with the preferred form of the invention heretofore described, the grab hooks 6 are hooked into the lengths of the chain as seen in Figures 7 and 8. In this case the tension is taken in the wire by pulling the lever down the same as above described in connection with the other method of tightening fence wire.

My invention may be constructed from steel or wrought iron, or any other suitable material and it is to be understood that the drawings and the accompanying descriptions are to be taken for illustrating purposes only since various other changes in size and construction may be resorted to without departing from the scope of my in-

ventive concept and that I am to be limited only by the scope of the subjoined claims, wherein

I claim:

1. In a wire stretcher, the combination with a hollow lever with one end formed into a post engaging spur and provided with a series of holes in the direction of its length with a pair of wire engaging hooks linked to a yoke like member provided with a hook prong, said prong being adapted to hook into the holes in the lever. 10

2. The device as claimed in claim 1 including a holding dog pivoted on a pivot lying on a diameter of the lever.

3. In a wire stretcher, the combination of a lever with one end formed into a post engaging spur and provided with a series of holes in the direction of its length, and provided with a slot at the end formed into a spur, a pair of wire engaging hooks linked to a yoke like member provided with a hook prong, said prong being adapted to engage the holes in the lever and a holding dog pivoted above the lever near the end of the aforesaid slot in the lever. 20

4. The device as claimed in claim 3, wherein the holding dog is provided with an inwardly curved spur which adapts the holding dog to contact a post or the like at a point immediately above the point that the said spur of the said lever engages. 25

JOHN A. SNODGRASS. 30
